Filed Mar. 2, 1961, Ser. No. 64,125

Term of Patent 7 years

(Cl. D9—2)

FIG. 1 is a perspective view of a fountain brush, showing our new design;

FIG. 2 is a side elevational view thereof;

FIG. 3 is a top plan view thereof;

FIG. 4 is an end elevational view thereof; and

FIG. 5 is an enlarged fragmentary sectional view taken on lines 5—5 of FIG. 2.

The extension arm is shown broken away in FIGS. 2 and 3 for convenience of illustration.

The side not shown is substantially like the side shown.

The dominant features of our invention are shown in full lines.

We claim:

The ornamental design for a fountain brush or similar article, substantially as shown, and described.
